(57) **CLAIM**

The ornamental design for a faucet unit, as shown and described.

DESCRIPTION

FIG. 1 is a perspective view of a first component of a faucet unit, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second component of a faucet unit, shown separately for ease of illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a perspective view of a first component and a second component of the faucet unit shown in a position of use.

The broken lines in the drawings depict portions of the faucet unit that form no part of the claimed design. The other broken lines shown in FIG. 17 show portions of the faucet unit and environmental subject matter that form no part of the claimed design.

1 Claim, 17 Drawing Sheets
